UNITED STATES PATENT OFFICE.

HENRY DOSS PATE, OF ABBOTT, TEXAS.

HORSE-COLLAR.

1,107,993.

Specification of Letters Patent. Patented Aug. 18, 1914.

Application filed July 8, 1913. Serial No. 777,898.

To all whom it may concern:

Be it known that I, HENRY D. PATE, a citizen of the United States, residing at Abbott, in the county of Hill and State of Texas, have invented new and useful Improvements in Horse-Collars, of which the following is a specification.

This invention relates to horse collars and more particularly to combined collars and hames.

The principal object of the invention is to provide simple and efficient means for attaching a pneumatic pad to the hames so that it may be readily removed.

Further objects of the invention will appear as the following description is read in connection with the accompanying drawing, which forms a part of this application, and in which:—

Figure 1 is an elevation of the combined collar and hames showing the pneumatic pad applied thereto. Fig. 2 is a transverse sectional view taken through one section of the pad. Fig. 3 is an elevation of the pad casing removed from the hames.

Referring more particularly to the drawing, 1 and 2 represent the separate hame sections each of which is provided with a vertically extending apertured projection adapted to receive the connecting strap or chain and also with a ring or loop at its lower end to receive the connecting strap for joining the lower end of the sections. Each section of the hame comprises a metallic plate curved to conform to the animal's shoulder and provided with a curved flange 3 which extends around the entire marginal edge of the plate. Each section is also provided with suitable tug hooks, ring turrets and like devices which form no part of this invention.

The pad consists of a casing formed in two sections 4 and 5 which are connected together at their upper ends by a strap or other flexible connecting element 6 which may carry a neck pad if desired. The sec-

tions 4 and 5 are made to conform to the outline of the hame sections 1 and 2 and are constructed similarly to the shoes of ordinary pneumatic tires, that is, their marginal edges are separated and provided with flange engaging ribs 7 which are suitably reinforced by curved metallic plates 8 or other similar or suitable devices, for a purpose to be hereinafter described. The marginal edges of these sections are hooked over the flanges 3, as will be seen from an inspection of Fig. 2, and the flexible bag is mounted between the hames and the casing, as shown at 9. These bags are inflated through separate valves 10 so that each pad may have the desired hardness or flexibility according to the various conditions which must be observed, among which is the condition of the animal's shoulders. By reinforcing the ribs 65 7 on the sections the casings are prevented from bending at the juncture of the rib with the body of the casing and the rib is thereby firmly held in engagement with the curved flange.

What is claimed is:—

A device of the class described comprising a pair of plates adapted to be movably connected together and curved to conform to the shoulders and neck of the animal, oppositely curved flanges formed at the marginal edges of the plate and extending outwardly, a pair of pneumatic casings connected together at one end and having rim engaging ribs at their marginal edges adapted to extend over the plate and removably engage the curved flanges of the plates, curved reinforcing plates embedded in said ribs, and independent pneumatic tubes arranged in each casing between the same and the inside of the associated plate.

In testimony whereof I affix my signature in presence of two witnesses.

HENRY DOSS PATE.
